Inventor,
William V. Orr.

By Kuhl, Smith, Brock, & West

Atty.

UNITED STATES PATENT OFFICE.

WILLIAM V. ORR, OF CLEVELAND, OHIO.

DUST-BAG CONNECTION FOR SUCTION-CLEANERS.

1,235,920.

Specification of Letters Patent. Patented Aug. 7, 1917.

Application filed December 1, 1916. Serial No. 134,278.

To all whom it may concern:

Be it known that I, WILLIAM V. ORR, a citizen of the United States, residing at Cleveland, in the county of Cuyahoga and 5 State of Ohio, have invented a certain new and useful Improvement in Dust-Bag Connections for Suction-Cleaners, of which the following is a full, clear, and exact description, reference being had to the accompanying drawings.

This invention relates to suction cleaners of the type wherein a movable casing having a motor, a pumping device, and an inlet mouth is moved about over the floor by 15 means of a handle, the air displaced by the pumping device being delivered into a porous bag, one end of which is secured to the casing and the other end to the handle. It is customary to attach this bag to the handle 20 by the use of an elastic member of some kind so as to maintain the bag taut at all times without impeding the movement of the handle, and also to permit the shortening of the bag which occurs upon inflation. Heretofore 25 it has been customary to employ a mere naked suspending spring, but the same has been liable to sway about and get in the way during the operation of the device, and is frequently caught upon articles of furniture 30 and distorted out of shape. The objects of the present invention are the provision of a neat, compact, and self-contained suspending device for this purpose; the provision of a spring so protected that it cannot be distorted or over-strained; while further objects and advantages will become apparent 35 as the description proceeds.

In the drawings accompanying and forming a part of this application, wherein I 40 have illustrated one embodiment of my said invention: Figure 1 represents a perspective view of a complete cleaner embodying my invention; Fig. 2 is a detail view of the suspending device, the bag being disconnected and a part of the handle being shown in section; and Fig. 3 is a cross sectional view on the line 3--3 of Fig. 2.

Describing the parts by reference characters, 1 represents the fan chamber and 2 the 50 nozzle of a suction cleaner, the same being supported upon suitable wheels 3, and guided by means of a handle 4, pivoted thereto by means of a yoke 5. 6 represents the dust bag which is provided at the upper end 55 with an attachment 7, which in the present embodiment serves both as a closure and as a

device for spreading the bag and as a means of support.

Secured to the side of the handle adjacent to the upper end of said bag is a housing 60 of sheet metal having an elongated cylindrical portion 10 parallel to the handle, and having projecting ears 11—12 to receive the screws or tacks whereby it is attached in place. In the present embodiment the handle itself is also channeled to some extent as shown at 13, so as to form with this housing a cylindrical chamber adapted for the reception of a compression spring 14, there being a slot 15 provided at one part of 70 the chamber, as for example between the side of the handle and the edge of the housing. A guiding block 16 is slidably inserted above said spring at the upper end of said housing and carries a laterally projecting eye 17 extending outside of the housing and adapted to be attached to the ring 18 carried by the attachment 7.

This arrangement always maintains the attachment 7 close to the handle 4 in a neat 80 and trim manner and permits the necessary shortening of the bag and movement of the handle, but without permitting distortion of the spring or catching of furniture. It will be understood that many changes in the construction may be made within the scope of 85 my invention.

Having thus described my invention, what I claim is:

1. In a suction cleaner, a casing, a handle 90 secured to said casing, an elongated housing carried by said handle, a spring in said housing, a connecting device attached to said spring and extending outside said housing, and a dust bag having one end attached to 95 said casing and the other end to said connecting device.

2. In a suction cleaner, a casing, a handle secured to said casing, an elongated housing carried by said handle, and having a slot in 100 its wall, a connecting device attached to said spring and projecting through said slot, and a dust bag having one end attached to said casing and the other end to said connecting device.

3. In a suction cleaner, a casing, a handle secured to said casing and having an elongated chamber formed with a slot in its wall, a spring in said chamber, a slideable member inside said chamber operatively connected 110 to said spring, a connecting device attached to said member and projecting through said

slot, and a dust bag having one end attached to said casing and the other end to said connecting device.

4. A dust bag connection for suction cleaners comprising an elongated housing adapted to be secured to the cleaner handle, a spring in said housing, a slideable member inside said housing operatively connected to

said spring, and a connecting device attached to said member and extending outside 10 said housing and adapted to have the dust bag secured thereto.

In testimony whereof, I hereunto affix my signature.

WILLIAM V. ORR.
